UNITED STATES PATENT OFFICE.

HENRY D. POWNALL, OF CINCINNATI, OHIO.

ICE MACHINERY.

1,180,529.

Specification of Letters Patent. Patented Apr. 25, 1916.

Application filed December 17, 1910. Serial No. 597,746.

To all whom it may concern:

Be it known that I, HENRY D. POWNALL, a citizen of the United States, residing at Cincinnati, in the county of Hamilton and State of Ohio, have invented certain new and useful Improvements in Ice Machinery, of which the following is a specification.

My invention relates to improvements in ice machinery.

10 One of its objects is to provide an improved cooling tank and ice mold system and construction.

Another object is to provide means to circulate fresh water to and from the ice molds during the freezing operation.

Another object is to provide in connection with a system for circulating fresh water through the molds during the freezing operation, means to remove from the circulating water the impurities concentrated therein by the freezing operation.

Another object is to provide improved means to insure during the freezing operation a circulation of fresh water through the ice molds and to agitate the water in the respective molds.

Other objects are to provide an improved cooling tank and ice mold construction, to provide for draining impure water from the molds, for separate control of air under pressure to the respective molds, to protect the fresh water conduits to the mold from freezing, and to release the ice from the molds.

35 It further consists in certain details of form, combination and arrangement, all of which will be more fully set forth in the description of the accompanying drawings, in which:

40 Figure 1 is a top plan view of two units of my improved ice producing apparatus, with the insulation omitted. Fig. 2 is a vertical section through one of the cooling tanks on line $v-v$ of Fig. 1, illustrating the insulation and the formation of ice in one of the molds. Fig. 3 is a plan view of the cooling tank bottom plate. Fig. 4 is a perspective view illustrating a modification of the cooling tank bottom. Fig. 5 is a per-

spective view of the coupling member by 50 which the fresh water conduits are connected to the ice molds.

In the accompanying drawings representing the preferred embodiment of my invention, A represents a series of cooling tanks 55 in which brine or other cooling medium is adapted to be contained and preferably circulated to freeze ice in the ice molds.

B represent the ice molds, one or more of which may be provided in each cooler tank. 60

In the preferred form of construction the tank bottom A' is perforated at a to provide an opening beneath each ice mold, and the lower edges of the side plates b of the molds are attached to the tank bottom by 65 angle plates a', and the bottoms b' of the molds are attached to the side walls b above the angle plates a', thus providing a chamber or recess b² beneath each mold opening downwardly. The bottom of the tank rests 70 upon T-bars D which in turn are supported by piers d, thus providing an open space beneath the tanks and ready access to the bottom of the tank and molds. Spaces E are provided between the respective molds, 75

and the molds and inner walls of the tank, and the cooling medium is preferably supplied to the respective tanks by means of trunk conduits F and branch conduits f controlled by valves f'. The cooling medium 80 fills and circulates through the spaces E and leaves the respective tanks through branch conduits g controlled by valves g', and a main conduit G by which it is returned to a brine cooler and thence back to the tanks by 85 conduit F. The lower portion of the spaces E are filled to about the level of the bottom of the molds with a plastic insulating material e such as pitch or asphalt preferably introduced in a semi-fluid state, which effectively seals all joints at the bottom of the tanks and molds and also prevents the cooling medium chilling the side walls of the recesses b², which might result in freezing the fresh water in the pipes entering said recesses. The upper portion of the spaces E are occupied by sills H which serve to support the mold lids h above the ice molds, 95

The outside walls of the cooling tanks are preferably protected by insulating material h' .

The bottom of each ice mold is perforated at the center and has attached thereto a coupling member I to which is attached a fresh water inlet conduit i and a fresh water exit conduit i' , the approach i^2 to which exit conduit in the upper face of the member I is such as to drain or conduct to said exit conduit any sediment or solid matter which may be concentrated in or settle to the bottom of the ice mold. The fresh water inlet conduits of the respective molds are connected to a main or trunk conduit J controlled by a valve J' and the respective fresh water exit conduits to a main or trunk conduit K controlled by a valve K' , which trunk conduits are connected to opposite ends or portions of a settling reservoir L which as illustrated is provided with a series of baffle plates l and valve controlled drain pipes l' and serve to separate from the fresh water any solid matter or sediment concentrated therein by the freezing operation in the ice molds, which sediment is drawn off from time to time through the pipes l' . Overflow pipes l'' lead from the reservoirs L, and a slight overflow is preferably maintained during the freezing operation, which serves to maintain a uniform level in the ice molds, and to separate any impurities having a tendency to float on the surface of the reservoirs L.

The trunk conduit K is provided with a branch pipe k controlled by a valve k' , which when valves J' K' are closed serves to drain the fresh water from the ice molds, and is adapted to be used to drain impure or sediment charged water from the molds, particularly during the latter stages of the freezing operation, when the unfrozen core is of small diameter, to enable the impure sediment charged water to be replaced with fresh clean water, or even if desired with distilled water to finally freeze into and close up the core. Drain cocks J^2 serve to drain the water from the conduits i when valve J' is closed.

M represents a fresh water supply or storage reservoir, in which is located a coil of pipe m connected at opposite ends to valve controlled brine pipes m' m^2 through which brine is adapted to be circulated from either cooling tank by means of a circulating pump m^3 . Fresh water enters reservoir M through pipe M' and is conducted therefrom to the ice molds through pipes m^4 m^5 . Air is preferably supplied under pressure by pipe N and escapes through orifices in the ends of the tubes n controlled by valves n' into the fresh water supply pipes i from whence it rises and escapes at the surface

of the water in the ice molds, thereby causing a circulation of water to and from the respective molds, and agitating the water in the molds to detach any solid matter or gas bubbles from the surface of the ice as it is forming. The current of water through the molds serves to conduct away the solid matter being rejected and concentrated by the freezing operation. I also preferably provide mechanically operated fresh water circulators K^2 which may be used either independently of or in conjunction with the air supply.

In operation cold brine is preferably supplied through pipe f to one or more units or cooling tanks, and after circulating through the tank is conducted away to a brine cooler by pipe g . The ice molds are filled with fresh or raw water from any source supplying water suitable for drinking purposes, said supply passing through the reservoir M where it is initially cooled and thence to the ice molds, and the valve m^6 regulated to secure a slight overflow at pipe l'' . Air is admitted through pipes N , n , and regulated at valves n' , and the freezing operation commences and proceeds as indicated in the right hand mold of Fig. 2 until only a small vertical core of fresh water above the pipes i i' remains unfrozen. Meanwhile a current of fresh water to and from the molds is maintained either by escape of air from the pipes n , or by the mechanical circulator K^2 , which removes all solid matter from the molds and deposits the same in the settling reservoir. Should the water in the molds become charged with sediment, particularly toward the end of the freezing operation, with liability of freezing the sediment into the ice, the valves J' K' are closed and the impure water from the molds drained off, and upon again opening the valves J' K' is replaced with fresh clean water and the freezing operation proceeded with until only a very small core remains unfrozen, when the ice may be withdrawn, or if desired, the fresh water circulation may be stopped, the water drained from the cores, and the cores again filled either with distilled water or fresh raw water and allowed to stand until the cores completely solidify, before removing the ice from the molds.

To remove the ice from the molds, the circulation of cold brine is cut off at valves f' g' and valves m^8 m^9 opened and circulating pump m^3 started, which causes the body of brine locked between valves f' g' to be circulated one or more times through the coil m where its temperature is raised and its negative heat transferred to the fresh water of the reservoir M, and said brine upon being returned to the cooling

tank A serves to loosen the ice from the molds and permit it to be removed, after which the molds are ready to be again filled with fresh water, the valves m^8 m^9 closed 5 and the valves f' g' opened and another freezing operation commenced.

The various fresh water reservoirs and conduits may be protected by insulation, not shown, to prevent undue loss of negative heat, care being taken however to prevent formation of ice in said reservoirs and conduits. 10

In the modification Fig. 4 the tank bottom A² instead of being formed from sheet metal is built up from sections a^5 a^6 of I-beam or other structural iron forms either riveted or welded together. 15

The apparatus herein illustrated and described is capable of considerable modification without departing from the principle 20 of my invention.

Having described my invention, what I claim is:

1. In an ice machine, a cooling tank in which a cooling medium is to be circulated, 25 an ice mold located in said tank, a chamber beneath said ice mold, a plastic insulating material occupying the lower portion of said tank and insulating the side walls of said chamber, fresh water inlet and exit conduits leading to and from said ice mold through said chamber, and means to supply air under pressure to said inlet conduit to maintain a circulation of fresh water to and 30 from said ice mold during the freezing operation. 35

2. In an ice machine, a cooling tank in which a cooling medium is to be circulated, said tank having a perforated bottom, a series of ice molds located in said tank above 40 said perforations so as to form downwardly opening chambers beneath said ice molds, and between the tank bottom and the bottom of said molds, a plastic insulating material occupying the lower portion of said tank and protecting the side walls of said chamber from the action of the cooling medium, and means to supply fresh water to 45 said ice molds through said chambers.

50 3. In an ice machine, a cooling tank in which a cooling medium is to be circulated, an ice mold located in said tank, a fresh water inlet conduit connected to the bottom of said mold, a fresh water exit conduit 55 connected to the bottom of said mold, a passage at the bottom of said mold adapted to conduct sediment to said exit conduit, and means to circulate fresh water to and from said mold.

60 4. In an ice machine, a cooling tank in which a cooling medium is to be circulated, an ice mold located in said tank, a coupling member attached to the bottom of said

mold, a fresh water inlet conduit connected to said coupling member, a fresh water exit conduit connected to said coupling member, a passage in the upper face of said coupling member to collect and conduct sediment to said exit conduit, and means to circulate fresh water to and from said mold through 65 said conduits. 70

5. In an ice machine, a cooler tank in which a cooling medium is to be circulated, said tank having a perforated bottom, an ice mold located in said tank and supported by means of its side walls above said perforation, the bottom of said mold being located above the lower end of the side walls thus forming a chamber beneath said ice mold, 75 an insulating material occupying the lower portion of said tank and insulating the side walls of said chamber, and a conduit adapted to supply fresh water to said mold connected thereto through said chamber. 80

6. In an ice machine, a cooling tank in which a cooling medium is adapted to be circulated, said tank having a perforated bottom, an ice mold located in said tank and supported by means of its side walls above said perforation, the bottom of said mold being located above the lower end of the side walls thus forming a chamber beneath said mold, and between the bottom of said mold and the bottom of said tank, and conduits to conduct fresh water to and from 90 said mold connected thereto through said chamber. 95

7. In an ice machine, a cooling tank in which a cooling medium is to be circulated, an ice mold located in and connected to the bottom of said tank, a valve controlled fresh water conduit connected to said mold through the bottom of said tank and protected from the refrigerating action of said cooling medium and adapted to supply fresh water to said mold, and means to withdraw the unfrozen water and concentrated impurities from said mold and to refill said mold with fresh water during the freezing operation. 100

8. In an ice machine, a cooling tank in which a cooling medium is to be circulated, an ice mold located in said tank, a valve controlled fresh water conduit connected to said mold and protected from the refrigerating action of said cooling medium and adapted to supply fresh water to said mold, means to maintain a uniform maximum fresh water level in said mold, and means to withdraw the unfrozen water and concentrated impurities from said mold and to refill said mold with fresh water at intervals during the freezing operation. 115

9. In an ice machine, a cooling tank in which a cooling medium is to be circulated, 120 an ice mold located in said tank, a valve

controlled fresh water inlet conduit leading to said mold, a valve controlled fresh water exit conduit leading from said mold, means to maintain a circulation of fresh water through said conduits to and from said ice mold, and means to withdraw the unfrozen fresh water and concentrated impurities from said mold and to refill the mold with fresh water during the freezing operation.

10. 10. In an ice machine, a cooling tank in which a cooling medium is to be circulated, an ice mold located in said tank, a valve controlled fresh water inlet conduit leading to said mold, a valve controlled fresh water exit conduit leading from said mold, means to maintain a circulation of fresh water through said conduits to and from said ice mold, and means to withdraw the unfrozen water and concentrated impurities from said mold and to refill the mold with fresh water at intervals during the freezing operation.

11. In an ice machine, a cooling tank adapted to contain a cooling medium, an ice mold located in said tank and externally in contact with said cooling medium, a fresh water conduit communicating with the lower portion of said ice mold, and means to remove fresh water charged with impurities from said ice mold and to supply pure fresh water to said mold during the freezing operation.

12. In an ice machine, a cooling tank adapted to contain a cooling medium, an ice mold located in said tank and externally in contact with said cooling medium, a fresh water conduit communicating with the lower portion of said mold and protected from the refrigerating action of said cooling medium, and mechanism to remove fresh water charged with impurities from said ice mold and to supply pure fresh water to said mold during the freezing operation.

13. An apparatus for making artificial ice comprising a refrigerating tank having one or more openings in the bottom thereof, one or more containers in said tank having their bottoms fitted over the openings therein and exposed to the atmosphere therethrough, said containers having extensions exposed laterally to the atmosphere and projecting through said openings, means for circulating a refrigerating liquid through said tank, and means for introducing air to said containers through said extensions.

14. An apparatus for making artificial ice comprising a refrigerating tank having one or more openings in the bottom thereof, one or more containers in said tank having their bottoms fitted over the openings therein and exposed to the atmosphere therethrough, said containers having extensions exposed laterally to the atmosphere and pro-

jecting through said openings, means for circulating a refrigerating liquid through said tank, and pipes connected with said extensions for supplying air and water to said containers.

15. An apparatus for making artificial ice comprising a refrigerating tank, one or more containers therein having their lower portions exposed to the atmosphere to provide non-freezing zones at the bottoms thereof, means for introducing air to said containers through said non-freezing zones, a water supply pipe connected with the non-freezing zones of said containers and with the source of water supply, and a valve in said pipe for discharging to waste the unfrozen water from said containers after the freezing operation is completed.

16. An apparatus for making artificial ice comprising a refrigerating tank having an opening in the bottom thereof, a container for the water to be frozen, said container being adapted to fit over said opening, and having its bottom exposed therethrough to the atmosphere, and means for clamping the container down upon the bottom of the refrigerating tank.

17. An apparatus for making artificial ice comprising a refrigerating tank having an opening in the bottom thereof, a container for the water to be frozen, said container being adapted to fit over said opening, and having its bottom exposed therethrough to the atmosphere, means around the bottom of the container for preventing leakage thereunder, and means for clamping the container down upon the bottom of the refrigerating tank.

18. An apparatus for making artificial ice comprising a refrigerating tank having an opening in the bottom thereof, a container for the water to be frozen fitting over said opening and having its bottom exposed therethrough to the atmosphere, said container having a marginal flange at the bottom thereof adapted to extend around said opening, means around said flange for preventing leakage thereunder, and means for clamping the container down upon the bottom of the tank.

19. An apparatus for making artificial ice comprising a refrigerating tank having an opening in the bottom thereof, a container for the water to be frozen, said container being adapted to fit over said opening, and having its bottom exposed therethrough to the atmosphere, and means for holding the container firmly upon the bottom of the refrigerating tank.

20. An apparatus for making artificial ice comprising a refrigerating tank having an opening in the bottom thereof, a container for the water to be frozen, said container

being adapted to fit over said opening, and having its bottom exposed therethrough to the atmosphere, means around the bottom of the container for preventing leakage 5 thereunder, and means for holding the container firmly upon the bottom of the refrigerating tank.

21. An apparatus for making artificial ice comprising a refrigerating tank having an 10 opening in the bottom thereof, a container for the water to be frozen, fitting over said opening and having its bottom exposed therethrough to the atmosphere, said con-

tainer having a marginal flange at the bottom thereof adapted to extend around said opening, means around said flange for preventing leakage thereunder, and means for holding the container firmly upon the bottom of the tank.

In testimony whereof I have affixed my 20 signature in presence of two witnesses.

HENRY D. POWNALL.
